UNITED STATES PATENT OFFICE.

GEORGE H. VAN WINKLE, OF HORNELLSVILLE, NEW YORK.

COMBINED LATCH AND LOCK.

SPECIFICATION forming part of Letters Patent No. 339,245, dated April 6, 1886.

Application filed April 15, 1885. Serial No. 162,345. (Model.)

To all whom it may concern:

Be it known that I, GEORGE H. VAN WINKLE, of Hornellsville, in the county of Steuben and State of New York, have invented certain new and useful Improvements in Combined Lock and Latch; and I do hereby declare the following to be a full, clear, and exact description of the invention, such as will enable others skilled in the art to which it appertains to make and use the same.

My invention relates to improvements in combined locks and latches, and more particularly to that class in which the latching mechanism is operated by a longitudinally-sliding spindle.

Heretofore in all classes of latches, except those employing an objectionable projecting lug from the heel of a pivoted latch, the door must be completely closed before the bolt can commence to enter the keeper. These latches have been found to be objectionable in that when a door is not slowly and carefully closed it will recoil from the jamb before the inertia of the latching mechanism has been overcome by the force of the spring, and thus the latch fails to enter the keeper. Again, the knob-spindle has been passed through an opening in the latch-casing for the purpose of enabling the spindle to operate the latch. This method, besides being expensive, is also objectionable in that the sliding spindle was liable to bind therein.

Heretofore in latches operated by a sliding spindle the means employed to retain the latch in a latched position until released by the longitudinal action of the spindle has been unsatisfactory in that too much force was required to disengage said latch; and, again, locking-latches have heretofore been inefficient in that when locked the door could still be opened by inserting a thin strip of metal behind the stop and retracting the latch by pressing against the inclined plane thereon; and, finally, where a cam has been used to operate the latch by turning the knobs, said cam has been placed on the outside of the rosette or escutcheon, where it was liable to pinch the finger of the person operating the latch.

The object of my present invention is to obviate the objections above noted by providing a neat, strong, and durable latch and

lock that shall combine simplicity and economy in construction with durability and efficiency in use; and with these ends in view my invention consists in the parts and combinations of parts, as will be more fully described, and pointed out in the claims.

In the accompanying drawings, Figure 1 is a view in horizontal section through a door and jamb, showing the spindles, latch-casing, and keeper in section. Fig. 2 is a detached view in perspective of the latch-casing. Fig. 3 is a similar view of the strike-plate. Fig. 4 is a detached view of the inner knob and knob-shank. Fig. 5 is a detached view of the outer knob and its shank. Fig. 6 is a detached view of the tube H. Fig. 7 is a detached view of the shaft M. Fig. 8 is a view in end elevation, showing the cam for operating the bolt H'. Fig. 9 is an enlarged view of the tumbler-carrier. Fig. 10 is a view in perspective of the rose-washer L. Fig. 11 is a view, partly in section, showing the latch-casing and locking mechanism, and Fig. 12 is a view of the key.

A represents a two-part cylindrical shell or casing that can be cast without the aid of a core, and is provided at its rear end with an elongated slot for the passage of the rear end of the operating-lever a. The two parts of this casing are secured together by the screw b, which latter passes through an opening in one section of the casing and enters a screw-threaded opening in the other section.

The section c of the casing A is provided with the face-plate d, the latter having screw-holes for the passage of the screws which secure the latch-casing within the mortise formed in the door, and with a recessed portion, d', in which the pivoted latch A' rests when in a closed position. This section also has semi-cylindrical depressions, which form part of the bearings for the trunnions of the bolt or latch A' and lever a. These bearings for said trunnions are made complete by similar semi-cylindrical depressions in the other section of the latch-casing.

The latch A' is shaped substantially as shown in the drawings, and is provided at opposite sides of its inner end with the laterally-projecting trunnions e, which latter rest in corresponding recesses or openings (before referred to) formed in the casing A, and is pro-

vided at its extreme inner end with the groove *f*, in which the outer end of the connecting-lever *B* rests. This connecting-lever *B* is provided with a longitudinal slot, through which 5 the bolt *b* passes, and is provided with a rounded outer end for engaging the latch or bolt *A'*, and at its opposite end with a rounded bearing, *b'*, with which the bifurcated or inner end of the lever *a* engages. This lever is curved 10 slightly, as shown, and is pivoted at *f*³ within the casing *A*, with its outer or longer end projecting through an elongated slot in the inner end of the latch-casing.

D is a spring, of any approved shape and 15 construction, secured to or located within the casing, and exerting its pressure directly against the lever *B*, and forming a fulcrum for said lever. Thus it will be seen that when the outwardly-projecting end of the lever *a* is 20 moved the length of its stroke the end of the lever *B* adjacent to the lever *a* will be moved a short distance in the opposite direction, and consequently cause the outer end of said lever *B* to bear against the portion of the latch *A'* 25 behind the trunnions of the pivotal latch. As soon as the outer end of the lever *B* passes behind the center of the trunnions of the pivotal latch the spring *D* forces the lever *B* away from said spring and turns the pivotal 30 latch around to a closed position. When the pivotal latch is in an open or locked position, the lever *B*, which connects the latch and lever *a*, rests in such a position as to prevent the possibility of the latch *A* moving to a closed 35 position without first moving the lever *a*, and hence when the latch is automatically opened by coming in contact with the keeper, as will be hereinafter described, it will remain open until the position of lever *a* is changed so as 40 to admit of the slight backward movement of the lever *B*.

The latch-casing is applied to the door, without reference to the thickness of said door, by bringing the outer edge of the recessed portion *d'* of the face-plate *d* on a line or flush with the outer face of the door. The strike-plate *E* is secured in a position corresponding to the position of the pivotal latch, and is provided, preferably at or near its longitudinal 45 center, with an outwardly-projecting lug, *g*, and an inwardly-projecting lug, *g'*, both of which are formed integral with the strike-plate. The lug *g* projects outwardly sufficiently far to allow for shrinkage of the door 50 and engage or come in contact with the beveled face of the pivotal latch *A'*, and is provided with a slightly-concaved inner surface, which permits the latch to move freely thereon. By thus placing the latch-casing in the 55 door, as above described, and providing the strike-plate with lugs *g* and *g'* and the latch-casing with recess *d'*, the pivotal latch can be operated from the toe, and no unsightly and otherwise objectionable lug projecting from 60 the heel of the latch is required.

When the door is being closed, the beveled surface *a*⁴ on the toe of the latch engages first

with lug *g*, and the latch is forced by this contact and the movement of the door to turn on its trunnions, and thus progressively with the closing action of the door enters the opening in the strike-plate or keeper, and thus being entered and secured by the mechanism enclosed in the latch-casing it is impossible for the reaction caused by slamming the door to take place soon enough to displace the bolt. 75

When the pivoted latch is in the above-described open or locked position, the lever *B*, which connects the latch and lever *a*, rests in such a position as to prevent the possibility of 80 the latch *A'* moving to a closed position until the lever *a* is first moved by the longitudinal action of the knob shanks.

F represents the outer, and *F'* the inner, knob, provided, respectively, with hollow cylindrical shanks *G* *G'*, which are made integral therewith, within which, when the latter are secured in position on opposite sides of a door, fits the cylindrical tube *H*, which latter forms a union or connection between the knobs and 90 a case for the tumbler carrier.

The hollow shank *G* of the knob *F* is provided with an elongated open slot, *h*, in which the bolt *H'* of the tube *H* rests, and with a screw-hole through which the screw *H*², which 95 rigidly secures the shank *G* to the tube *H*, passes. The other shank, *G'*, of the knob *F'* is provided with an elongated open slot, *i*, in which the cam *I*, rigidly secured to or made integral with the tube *H*, rests, and with a transverse 100 closed slot, *I'*, in which the outer end of the lever *a* rests. This shank *G'*, which is attached to the inner knob, is not rigidly secured to the tube *H* in such a manner as to prevent it from moving independently of said tube, but is 105 loosely secured thereon, so as to permit it to move longitudinally thereon, the slot *i* and cam *I* preventing said spindle from rotating or turning independently of said tube.

The tube *H* is open at both ends, and is provided with an opening for the passage of the bolt *H'*, and with an opening or slot, *J*, corresponding in position to but greater in size than the slot *I'* in the shank *G'*, whereby the shank is permitted to move longitudinally, 115 and carry with it the lever *a*, without interfering with or moving the tube *H*. The knob *F* and shank *G'* are prevented from being wholly withdrawn from the tube *H* by the lever *a*, which latter, as before stated, passes 120 through the shank of the knob, and prevents the removal of the same until after the latch-casing, with its inclosed parts, have been partly withdrawn or removed.

L is a rose-washer secured to the outer face 125 of the door, and provided with an inwardly-projecting sleeve, *L'*. This sleeve is provided with an opening, *L*², corresponding in shape and size to the rear end of the latch-casing *A*, and adapted to receive said end and hold it 130 against displacement, and when said latch-casing is thus inserted and secured at the other end by screws passing through the face-plate *d* the rosette *L* cannot be removed even if the

screws in said rosette are drawn. The sleeve L' is also provided with the double-inclined plane or V-shaped slot L³, against which the V shaped cam I of the tube H bears. When the parts are in their normal positions, or at rest, the cam I rests at the base or juncture of the two planes L³; and hence it will be seen that by turning either knob to the right or left the cam I is caused to ride up one of the inclined planes L³ and move the tube H and both knobs longitudinally. As the rear end of the lever a rests within the slot I' of the shank G', it follows that when the knobs are moved inwardly the lever a is moved and unlatches the latch A'. This same result is accomplished by pushing directly inward on the outer knob or pulling on the inner knob. The rose L is also provided with a shoulder, j, against which the bolt H' is adapted to abut and prevent the outer knob, F, and the tube H, rigidly secured thereto, from being forced inwardly. This bolt is operated by mechanism located inside of the tube H, to be herein-after explained, and is adapted to prevent the latch A' from being actuated by any person on the outside of the door without employing a key especially constructed for the purpose.

As before stated, the knob F' and its shank G' are free to move longitudinally independently of the tube, and hence when the outer shank, G, and its knob F are locked against movement the inner knob, F', and shank G' can be drawn out or away from the door and operate the lever a without disturbing or moving the outer knob. When the door is closed, the latch is thrown out to its locked position, and cannot be turned by the outer knob without the use of a key constructed for the purpose.

M is a shaft constructed to fit snugly within the tube H, and provided with a reduced screw-threaded end, m, which latter projects from the inner end of the tube H into the knob F', and on which the nut K is secured. This nut fits snugly within a cylindrical recess formed in the knob, and is screwed home on the screw-threaded end m of the shaft M, so as to enable the shaft M, which operates the bolt H', to be turned from the inside—that is, to be operated from the inside of the house without the necessity of employing a key. This nut K is provided with a rib or thumb-piece, K', for convenience in turning the same, and the knob F' is provided with a stop, k³, which latter limits the rotary movement of said nut. This shaft is cut away to form a shoulder, m², which latter corresponds to the opening I' formed in the shank G', and forms a bearing for the end of the lever a. A portion of this shaft between the shoulder m² and the knob F' is cut away for quite a distance, as shown at m³, to permit the shank G' to be moved longitudinally and carry with it the lever a when the tube H is locked by the bolt H against longitudinal movement. The bolt H' is thrown or moved to an open position by the turning of the shaft M, and this turning of

the shaft brings the cut-away portion m³ of said shaft directly in front of the end of the lever a. When the shaft is turned back, so as to withdraw the bolt H', the cut-away portion m³ is moved to one side of the lever a, and the shoulder m² is brought into position on one side of the lever, and the shoulder m³ on the other side of said lever, and hence it is necessary for the tube H and shaft M, inclosed within said tube, to move longitudinally before the lever can be moved. This movement of the tube and shaft can be accomplished (when the bolt H' is in its unlocked position) by turning either knob.

The shaft M is provided with an eccentric, m⁴, on which the bolt H' is journaled, and by which said bolt is moved, and is also provided with a reduced end, n, having an angular recess therein, in which a correspondingly-shaped projection on the tumbler-carrier N rests. The shaft M is also provided on the reduced end, near the eccentric m⁴, with an annular groove for the reception of the end of the screw H², which holds the shaft M in position. This reduced end of the shaft M passes through the coupling O, which latter is rigidly secured to the tube H by the screw H², before referred to. This coupling is provided with a slot, in which the bolt H' is seated and moves, and is provided at its outer end with one or more slots, n⁵, adapted to register with the tumbler or tumblers secured to the tumbler-carrier.

The tumbler-carrier N consists, essentially, of a cylinder fitting snugly within the outer end of the tube H, and secured against displacement by the guard N³ at its outer end, and the shaft M at its inner end. This carrier is provided at its inner end with an angular projection, before referred to, for coupling it with the shaft M, and with one or a series of spring-actuated tumblers, which latter are seated within longitudinal slots formed in the periphery of the cylinder. These tumblers register with the slots n⁵ of the coupling O, and also with the slots n⁴ of the guard N³, which is rigidly secured to tube H. The springs which actuate the tumblers bear at their inner ends against a resisting washer, which is coiled into the peripheral slot in the tumbler-carrier, and hold the outer ends of the tumblers in the slots n⁴ of the guard N³ when the bolt H' is in a locked position, and prevent said bolt from being withdrawn without first moving the tumblers out of the slots n⁴ of the guard N³. This necessitates the employment of a key, P, which latter is adapted to enter the outer end of the guard and move the tumblers out of the slots n⁴ of guard N³ and turn the carrier, which, as before stated, turns the shaft M.

The tumbler-carrier is constructed to receive the key P, and is provided with a post having an angular surface with which a similar-shaped surface within the hollow key engages. The outer end of the key is constructed to engage the tumblers and move them until they are all clear of the slots in the guard N³, while

the angular-shaped surfaces on the key-post and in the key are for the purpose of turning the tumbler-carrier after the tumblers have been withdrawn from the guard. When the tumblers are moved out of the slots n^4 , they rest between adjacent ends of said guard and the coupling O. The key must necessarily be of a certain size to operate the lock, and hence if a key be employed that was not constructed for the particular lock, or if an attempt be made to pick the lock, the tumblers, if moved a fraction too far, will enter the slots n^5 of the coupling O and prevent the tumbler-carrier from turning, and consequently prevent the shaft from turning.

An annular recess is made in the outer end of the tumbler-carrier, at the base of the key-post, to allow the key to be inserted far enough to engage the shoulders on the ends of the tumblers, thus avoiding the necessity of making deep notches in the key. These shoulders on the ends of the tumblers are all of different depth, made so to prevent picking, and the key must be fitted to press against them, and at the same time bring the ends of the several tumblers all even. When the tumblers are thus pushed in by a properly-fitted key far enough to clear the slots in the guard N^3 , the key is prevented from pushing them farther in by contact with the end of the key-post within the key. The key is then turned to unlock the door, as above described.

The several tumblers being provided at each end with different-depth shoulders, and being interchangeable in the several longitudinal slots in the tumbler-carrier, and also reversible endwise and sidewise, it is evident that a large number of permutations can be made, which allows the same shaped tumblers to be used in a large number of locks, but all requiring differently-fitted keys. The end of the tube H which incloses the tumbler-carrier rests within the outer knob, F, with the end of said carrier in close proximity to an opening formed centrally within said knob for the introduction of the key.

From the foregoing it will be seen that when the latch A' is in an open position without being locked by the mechanism inclosed within the knob spindles it is securely held against accidental displacement, and is capable of withstanding any ordinary pressure. When in this position, it can be withdrawn from the keeper by simply turning either knob, or pushing on one knob or pulling on the other. When, however, the latch A' is locked by the bolt H', either by turning the nut K on the inside, or a key, P, from the outside, it is impossible to move it or unlock it from the outside of the door without employing a key especially constructed to fit the tumbler-carrier and the tumbler or tumblers carried therein. When the door is in this locked position, the cut-away portion m^3 of the shaft M is over the outer end of the lever a, and hence the said lever and the latch A' can be moved by sim-

ply pulling on the knob F', which of course is located inside of the room or house.

The face-plate of the lock-casing and the strike-plate are each provided with a series of segmental edges, which permit the mortises therefor to be cut by a boring-tool.

It is evident that numerous changes may be made in the form and arrangement of the several parts without departing from the spirit and scope of my invention; hence I do not wish to limit myself strictly to the construction herein set forth; but,

Having fully described my invention, what I claim as new, and desire to secure by Letters Patent, is—

1. The combination, with a strike-plate having inwardly and outwardly projecting lugs, of a pivoted latch, and devices for operating the latch.

2. The combination, with a strike-plate having a lug projecting outwardly from the face of the plate at right angles thereto, of a latch-casing, and a latch, substantially as described, pivoted within said casing and adapted to be turned outward by contact with said lug.

3. The combination, with a strike-plate having inwardly and outwardly projecting lugs, of a pivotal latch having a beveled face, and devices for operating the latch.

4. The combination, with a strike-plate having a lug projecting outwardly from the face of the plate at right angles thereto, of a latch-casing having a recess at its outer end, and a latch adapted when closed to rest within said recess flush with the outer surface of the latch-casing.

5. The combination, with a strike-plate provided with a lug having a rounded bearing-face, the said lug projecting outwardly from said plate at right angles thereto, of a latch-casing, a latch, substantially as described, pivoted to said casing and adapted to be moved outwardly by contact with said lug.

6. The combination, with a strike-plate having outwardly and inwardly projecting lugs, of a pivoted latch having an inclined face, and a latch-casing having a recess for the reception of the pivoted latch.

7. The combination, with a latch-casing and a pivoted latch having a groove formed therein near its pivotal point, of an operating-lever pivoted within the case, a lever connecting the operating-lever and pivoted latch, and a single spring bearing against the connecting-lever for holding the latch in open and closed adjustment.

8. The combination, with a latch-casing and a pivoted latch having a groove formed therein, of a lever pivoted within the latch-casing and projecting through one end thereof, a lever connecting the lever and latch, a spring bearing against and forming a fulcrum for said connecting-lever, and a longitudinally-sliding spindle for operating the lever.

9. The combination, with a two-part casing

- and a latch pivoted therein, of an operating-lever partly located within said casing and projecting through one end thereof, a lever connecting the latch and lever, a screw connecting the two parts of the casing and passing through a slot in the connecting-lever, and a spring forming a fulcrum for said connecting-lever, substantially as set forth.
10. The combination, with a latch and a longitudinally-sliding spindle for operating the latch, of a bolt located within the spindle and adapted to lock the same against movement.
11. The combination, with a latch and a longitudinally-sliding spindle for operating the same, of a bolt for locking the spindle against longitudinal movement, and devices located within the spindle for operating said bolt.
12. In a latch operated by a longitudinally-movable spindle, the combination, with a latch, two knobs having independent shanks, and devices connecting the said shanks and forming a spindle, of a lock located within said hollow shanks for locking the outer knob against movement, and devices for operating said lock either on the inside or outside of the door, substantially as set forth.
13. A rose-washer provided with an inwardly-projecting sleeve, the latter having an opening for the reception of the inner end of a latch-casing.
14. The combination, with a latch and a latch-casing, of a rose-washer having an inwardly-projecting sleeve, the latter provided with an opening for the reception of the inner end of the latch-casing, and a longitudinally-sliding spindle for operating the latch.
15. The combination, with a latch and latch-casing, a rose-washer, and a sleeve secured to said rose-washer and provided with an opening for the reception of one end of the latch-casing, and with a V-shaped slot, of a sliding spindle carrying a cam adapted to move against the surfaces of the V-shaped slot.
16. The combination, with a latch and a rose-washer having a shoulder thereon, of a longitudinally-sliding spindle, and a bolt located within said spindle and adapted to engage the shoulder on the washer and lock the spindle against longitudinal movement.
17. The combination, with a latch and a lever for operating the latch, of knobs, each having a shank, and devices, substantially as described, connecting the knobs, whereby they are permitted to move simultaneously for operating the latch, or the inner knob is permitted to move independently of the outer knob for operating said latch.
18. The combination, with a latch, a lever for operating the latch, and the knobs and knob-shanks, of a tube rigidly secured to one shank and passing through the other shank, and provided with a slot for the end of the latch-operating lever, a cam secured to said tube, and a rigid device having a cam-slot with which the cam on the tube engages, whereby the tube is moved longitudinally, substantially as set forth.
19. The combination, with a latch having an operating-lever, knobs, and knob-shanks, of a tube rigidly secured to one knob-shank and loosely connected with the other shank, a device, substantially as described, located within said tube and provided with a cam, and a bolt operated by said cam and adapted to engage a stationary object secured to the door, whereby the outer knob can be locked against movement, substantially as set forth.
20. The combination, with a latch having an operating-lever, the knobs and knob-shanks, of a tube connecting the shanks, a shaft located within the tube, a bolt operated by said shaft for locking the outer knob against longitudinal movement, and tumblers operated by a key for locking the shaft against rotary movement, substantially as set forth.
21. The combination, with a latch having an operating-lever, and the knobs having separate shanks, of the shaft, the nut secured on one end thereof, the tumbler-carrier connected to the opposite end of said shaft, tumblers for locking said shaft against movement, and a key for operating the tumblers, substantially as set forth.
22. A latch-casing made of two elongated separable sections, each section being semi-circular in cross-section, and each provided with registering semi-cylindrical depressions, forming bearings for the latch and operating-lever trunnions, substantially as set forth.
23. The combination, with a tumbler-carrier and tumblers and the shaft, of a washer located in a slot in the periphery of the carrier, and springs bearing against said washer and tumblers, substantially as set forth.
24. The combination, with a pivoted bolt and a lever, of a lever connecting the lever and bolt, and a yielding fulcrum for said connecting-lever, substantially as set forth.
25. The combination, with a latch having an operating-lever, knobs, and knob-shanks, of a tube connecting the shanks, a shaft located within the tube, a bolt operated by said shaft for locking the outer knob, tumblers for locking the shaft, and the guard N, substantially as set forth.
26. The combination, with a latch having an operating-lever, the knobs and knob-shanks, of a tube connecting the shanks, a shaft located within the tube, a bolt operated by said shaft for locking the outer knob against longitudinal movement, tumblers operated by a key, and a coupling, O, having slots n, substantially as and for the purpose set forth.
